UNITED STATES PATENT OFFICE.

MARY A. HOFF, OF VINTON, IOWA.

SWINGING CAR-STEP.

1,075,785.

Specification of Letters Patent. Patented Oct. 14, 1913.

Application filed July 30, 1913. Serial No. 732,095.

To all whom it may concern:

Be it known that I, MARY A. HOFF, a citizen of the United States, residing at Vinton, in the county of Benton and State of Iowa, have invented certain new and useful Improvements in Swinging Car-Steps; and I do hereby declare the following to be a full, clear, and exact description of the invention, such as will enable others skilled in the art to which it appertains to make and use the same.

This invention comprehends improvements in swinging car steps and relates more particularly to those of the type which are secured to the stationary steps and act as a supplemental step, which may be raised and lowered at will.

One of the objects of the invention is to provide a swinging car step of this type, which will be simple in construction, cheap to manufacture and very practical.

Another and more specific object of the invention is to provide a swinging car step which is hingedly secured to the lowermost riser of a set of stationary steps, and which, when not in use, may be swung into a vertical plane against the riser where it will not be in the way.

With these and other objects in view, as will become more apparent as the description proceeds, the invention consists in certain novel features of construction, combination and arrangement of parts as will be hereinafter fully described and claimed.

For a complete understanding of my invention, reference is to be had to the following description and accompanying drawings, in which—

Figure 1 is a vertical sectional view through a set of stationary car steps, showing my improved swinging step secured thereto, Fig. 2 is a front elevation of a set of car steps with my attachment applied thereto, Fig. 3 is a fragmentary vertical section, showing my improved step in its inoperative position, Fig. 4 is a horizontal section taken on the plane of line 4—4 of Fig. 1, and Fig. 5 is a detail view of the part to be hereinafter fully described.

Referring in detail to the drawing by numerals 1 designates a side of a car, 2 a platform thereof and 3 the stationary steps, which are of the usual construction and which are provided with risers 4 and 4'.

In carrying out my invention I provide a

swinging step 5, which is secured by means of the hinges 6 to the forward side of the lowermost riser 4, adjacent the lower edge thereof. The rear edge of the step 5 and lower edge of the riser 4 are beveled, as indicated by the numeral 7 so as to permit of the swinging step being moved into a horizontal plane. The ends of the riser 4 terminating in spaced relation to the side plates 8 of the stationary steps, as clearly shown in Fig. 4. Angular plates, generally designated 9 having horizontal sections 10 and upright sections 11 are secured to the top of the stationary step 5 adjacent the ends thereof. A link 12 is connected to each of the plates 9 by means of a bolt 13 and nut 14. Said bolt extends through the portions 11 of the plates 9 and through the links 12, the nut being threaded on the end of the bolt in engagement with the links. The nut being larger than the width of that formed by the side bars of the links effectually prevents said links becoming detached from the plates 9. A rod 15 extends longitudinally under the lowermost stationary step 3 and is fixed at its ends to the side plates 8 of the stationary steps. The links 12 pass around the rod 15 and form braces for the step 5 when the latter is disposed in its operative position. These links and the portions 11 of the plates 9 pass between the ends of the riser 4 and the side plates 8 when the step is swung into its inoperative position, as shown in Fig. 3.

To raise and lower the step 5, I provide a rod 16, which is connected at its lower end to an arm 17 which extends outwardly beyond the free longitudinal edge of the step 5 adjacent one end thereof. The rod passes through a bracket 18 secured to the side of the car and has a handle 19 formed upon its upper end. When the step is in its raised position, the handle 19 engages a spring 20 which is also secured to the side of the car. When it is desired to lower the step, the rod 16 is swung outwardly from engagement with the spring 20 and then forced downwardly. When the step assumes a horizontal position, the handle 19 is in engagement with the top of the bracket 18, and it will therefore be apparent that the rod 16 acts as a brace for the step.

From the foregoing description taken in connection with the accompanying drawing, it is evident that I have provided a very

simple and practical swinging car step adapted for attachment to a set of stationary car steps, so as to aid passengers in mounting and dismounting.

5 While I have shown and described the preferred embodiment of my invention, it will be understood that minor changes in construction and arrangement of parts may be made without departing from the scope 10 and spirit of the invention as claimed.

Having thus described my invention, I claim:

15 The combination with a set of stationary car steps including a pair of side plates and a riser terminating short of said plates, of a swinging car step, hinges secured to the top of the swinging step adjacent the rear edge thereof and to the front of the riser adjacent the lower edge thereof, the op-

posed edges of the car step and riser being 20 beveled, a pair of angular plates secured to the top of the swinging step adjacent the ends thereof, a pair of links, means for connecting one link to each of the angular plates, a rod fixed at its ends to the side 25 plates of the stationary steps and passing through said links, an operating rod connected at its lower end to the swinging step and means for supporting the upper end of the operating rod, an upward movement of 30 the operating rod causing the swinging step to be moved into a vertical plane.

In testimony whereof I affix my signature in presence of two witnesses.

MARY A. HOFF.

Witnesses:

MARION CALDWELL,
D. C. KNUPP.
